UNITED STATES PATENT OFFICE.

ALBERT NELSON, OF BUFFALO, MINNESOTA.

OPERATING MEANS FOR MUSICAL INSTRUMENTS.

Application filed July 12, 1926. Serial No. 121,873.

This invention relates to musical devices and means and methods for operating the same.

It is the general object of this invention 5 to provide means for permitting a single operator to play two or more instruments at the same time.

It is more specifically an object to provide 10 a musical device having in combination an instrument of the viol type, a wind instrument of the type having a playing slide and means for so positioning said instruments that the former can be bowed and the latter blown at the same time by a single operator.

15 It is a further object to provide in such a device means whereby the former instrument can be swung as it is played to operate the slide of the latter instrument.

20 Yet another object is to include in such a device an indicator operated by the swinging movement of the former instrument to indicate the position of the playing slide of the latter instrument.

25 These and other objects and advantages of the invention will more fully appear from the following description made in connection with the accompanying drawings in which like reference characters refer to the same or similar parts throughout the various views 30 and in which

Fig. 1 is a view in side elevation of the device, the movable parts of the device being shown in full lines in one position and in dotted lines in another position;

35 Fig. 2 is a view showing a portion of the device in end elevation;

Fig. 3 is a vertical section taken on the line 3—3 of Fig. 1, as indicated by the arrows; and

40 Fig. 4 is a section taken on the line 4—4 of Fig. 1, as indicated by the arrows.

In the drawings, the seat of a chair or similar support is indicated by the numeral 1. Secured at one side of the chair by suitable thumb screws a clamp 2 is provided having bellied portions adapted to accommodate the two legs of an inverted substantially U-shaped standard 3. The standard 3 is preferably composed from a solid rod and projects upwardly from the seat 1 to a position adjacent the position that a person's head would take if he were sitting on the seat. An instrument of the type having a playing slide, such as the slide cornet 4, is held at the top of standard 3 by means of a clip 5 and by the hook brackets 6 extending through the

respective legs of standard 3 adjacent the top thereof and secured to the legs preferably by wing nuts. An instrument of the viol type, such as the violin 7, is provided and has secured thereto, at its base, clamps 8 to which sleeve 9 is secured. Arm 10 preferably rigidly secured to the two legs of standard 3 has a horizontally extending portion at one side thereof with a shoulder 10^a formed thereon, the portion outward from the shoulder 10^a being reduced in diameter and forming a pivotal portion extending through the sleeve 9. The extreme outer end of the pivotal portion of the arm 10 is threaded and thumb screw 11 is screwed thereon adapted to hold the sleeve 9 on the pivotal portion of the arm. 60

65 Secured to the legs of the standard 3 by clamp 12 and appropriate thumb screws, an arm 13 is provided curving outwardly from the standard 3 and upwardly therefrom, the free end of the arm being horizontally apertured to receive a horizontally extending bolt or pivot member 14. The outer end of the

70 instrument of the viol type, outward from the fingering portion thereof, has an arm 15 secured thereto. A link 16 is pivoted at one end to the free end of the arm 15 and has its other end pivotally secured to one end of an angular arm 17, the other end of the arm 17 being rigidly secured to one side of the flange 75

80 of a flanged sleeve 18 mounted on the bolt 14 for pivotal movement thereon. Arms 19 are rigidly secured to the other side of the flanged sleeve 18 and extend substantially at right angles to the arm 17. Arm 17, flanged sleeve 85

90 18 and arms 19 constitute in effect a bell crank lever. The free ends of the arms 19 are pivotally secured to an arm 20 having one end thereof rigidly secured to the handling 95

bar 21 of the playing slide of the instrument 4. Compression spring 22 extends around link 16, the ends of the spring bearing against the ends of the arms 15 and 17 pivotally connected to the link 16. A tension spring 31 100

has one end secured to the outer end of the arm 20 and its other end secured to an eye secured in turn to one leg of the standard 3.

An outwardly extending angular rod 23 is rigidly secured adjacent the outer end of the arm 13 and has secured thereto at the angularly horizontally extending portion thereof a vertically disposed angular arm 24 having a vertically extending indicating scale 25 divided into eight gradations suitably numbered secured thereto. Brace 26 extends between the rod 23 and the arm 24, while brace 105

90

95

100

105

110

27 extends between the angular portions of the rod 24, said braces giving rigidity to the indicator structure. A vertically disposed slideway 28 is secured adjacent the indicator 5 25 at one side thereof and has slidably mounted thereon a sleeve 29 having a horizontal projection at the indicator side thereof projecting partially over the indicator, said sleeve 29 and the horizontally projecting portion thereof forming an indicator pointer. Link 30 is pivotally connected at one end to the sleeve 29 and is pivotally connected at the other end to a projecting portion 17^a formed on the arm 17.

15 A tube 32 having an outwardly flaring upper end is placed immediately below the saliva drain 33 of the instrument 4 and is suitably secured to the clamps 2 and 12. The positioning of the instrument 7 of the viol type 20 in respect to the instrument 4 of the type having a tuning slide is such that the instrument 7 can be held by an operator in convenient position for bowing while at the same time an operator can press his mouth against 25 the mouthpiece 34 of the instrument 4.

The operation of the device is as follows:—

An operator may sit upon the seat 1 of the chair and press his lips against the mouth-piece 34 of the playing slide instrument, 30 may hold the outer end of the viol type instrument with his left hand and may hold a bow for bowing the viol instrument in his right hand. The viol instrument can then be fingered in the usual manner and bowed in the usual manner while the operator at the same time can blow the wind instrument 4. As the operator plays the two instruments, he may swing the outer end of the viol instrument about the pivotal portion of 40 the arm 10, thereby transmitting motion through the arm 15, link 16, bell crank lever 17, 18 and 19 and arm 20 to move the playing slide of the instrument 4. The tone of the wind instrument 4 can accordingly be 45 changed or varied as the outer end of the instrument 7 is swung upwardly or downwardly. At the same time instrument 7 is swung, motion will be transmitted from the arm 17 to the link 30 and indicating pointer 29. 50 Pointer 29 will accordingly move to various positions on the indicating scale 25 as the playing slide of instrument 4 takes various positions. As the indicating scale is divided up into eight various denominative portions 55 designated by different numbers, it can be seen that the operator of the device can readily tell by looking at the indicating scale the exact position of the playing slide of the instrument 4.

60 Spring 31 will normally hold the parts of the device in the position shown in full lines in Figs. 1 and 3, but the spring can be readily stretched so as to permit the movement of the parts of the device to the position shown 65 in dotted lines in Figs. 1 and 3 or to any in-

termediate positions. The spring 32 bearing against the arms 15 and 17 will take up lost motion in the device which might occur between the pivots connecting the arms 15 and 17 to the link 16. The tube 32 will provide a 70 convenient drain for any saliva that may collect in the wind instrument 4. Various adjustments may be made to the standard 3 in the clamp 2 so that the device can be played by persons of various heights. Arm 75 13 is also capable of adjustment on the standard 3 by means of the clamp 12.

Although the device is shown as having in combination but two musical instruments, various attachments may be connected to the 80 bell crank lever so that other instruments may be played by motion transmitted thereto through swinging movement of the viol type instrument 7.

By means of the indicating scale the two 85 instruments can be played together by a single operator very accurately. The inventor has abundantly demonstrated the operation of the device in actual practice and has found the same to be very effective and successful as a novel musical device. The device is strongly made and will hold up under 90 continued usage. The parts are few and the construction is simple.

It will, of course, be understood that various 95 changes may be made in the form, details, arrangement and proportions of the various parts without departing from the scope of the present invention which, generally stated, consists in the matter shown and described 100 and set forth in the appended claims.

What is claimed is:

1. A musical device having in combination, several musical instruments and means for transmitting a swinging movement which 105 may be given to one of said instruments when played to operate said other instruments.

2. A musical device having in combination an instrument of the viol type, a wind instrument of the type having a playing slide and means for transmitting a swinging motion imparted to said viol type instrument as 110 played to operate the playing slide of said wind instrument.

3. A musical device having in combination, an instrument of the viol type, an instrument of the type having a playing slide and means adapted to be operated by a single operator for playing both of said instruments 115 at the same time.

4. A musical device having in combination, an instrument of the viol type and a wind instrument of the type having a playing slide, means for so positioning said instruments that said first mentioned instrument can be bowed and said second mentioned instrument blown at the same time by a single operator and means for operating 120 the playing slide of said second mentioned 125 instrument.

instrument from motion imparted thereto by swinging movement of said first mentioned instrument as it is played.

5. The structure defined in claim 3 and an indicator also operated by a swinging movement of said first mentioned instrument, said indicator showing the position of the playing slide of said second mentioned instrument.

10. 6. In combination with a bowed instrument of the viol type and a wind instrument of the type having a playing slide, a vertically adjustable standard adapted to hold said instruments in such relation that said first mentioned instrument can be bowed and said last mentioned instrument blown at the same time by a single operator, the base of said first mentioned instrument being pivoted to said standard and means for operating the 15 tuning slide of said second mentioned instrument from movement imparted thereto by swinging movement of said first mentioned instrument.

20. 7. A device for permitting a single operator to play two musical instruments at the same time having in combination, an instrument of the viol class and an instrument of the class having a playing slide, a standard adapted to hold said instruments in operative position, means for pivoting the base to said first mentioned instrument to said standard and means for connecting the fingering end of said first mentioned instrument to the playing slide of said second mentioned instrument so that as the fingering end of said first mentioned instrument is swung, said playing slide will be slid to various positions.

25. 8. A device for permitting a single operator to play two musical instruments together having in combination, an instrument of the viol type, an instrument of the type having a playing slide, a standard upon which said instruments are adapted to be mounted, means for pivoting the base of said first mentioned instrument to said standard, a bell crank lever pivotally mounted in relation to said standard, one arm of said bell crank lever being pivotally connected to the playing slide of said second mentioned instrument and means for pivotally connecting the other arm of said bell crank lever to the fingering end of said first mentioned instrument.

30. 9. The structure defined in claim 7 and an indicating scale rigidly mounted adjacent the fingering end of said former instrument and an indicating arm pivotally connected to one end of said bell crank lever and movable thereby adjacent said scale to indicate the position of said playing slide on said second mentioned instrument.

60

10. The structure defined in claim 7 and resilient means interposed between one arm of said bell crank lever and said standard, said resilient means being adapted to normally force the movable parts of said device to such a position that said playing slide will stand in an extreme position.

65

11. A device for permitting a single operator to play two musical instruments having in combination, an instrument of the viol type, an instrument of the type having a playing slide, a vertical standard to which said second mentioned instrument is secured and to which said first mentioned instrument is pivoted at its base, an arm secured to said standard and projecting outwardly therefrom adjacent said instruments, a bell crank lever pivoted to the free end of said arm, an arm secured to the free end of said first mentioned instrument, a link pivotally connected to said last mentioned arm and one arm of said bell crank lever, the other arm of said bell crank lever being pivotally connected to said playing slide.

70

12. The structure defined in claim 10 and a vertical indicating scale rigidly connected to the outer end of said first mentioned arm, a guide extending longitudinally of said scale, a pointer slidably mounted on said guide, and a link pivotally connected to said pointer and to one arm of said bell crank lever.

75

13. The structure defined in claim 7 and a tube mounted on said standard below said second mentioned instrument and adapted to carry off saliva from said instrument.

80

14. The combination with a bowed instrument of the viol type and a wind instrument of the type having a playing slide, of a vertically adjustable standard to which said first mentioned instrument is pivoted at its base for swinging movement and to which said second mentioned instrument is secured, an arm adjustably secured to said standard and projecting outwardly therefrom adjacent said instruments, a bell crank lever pivoted to the free end of said arm, an arm secured to the free end of said first mentioned instrument, a link pivotally connected to said second mentioned arm and to one arm of said bell crank lever, the other arm of said bell crank lever being pivotally connected to said playing slide and means for taking up the play between said second mentioned arm and the first mentioned arm of said bell crank lever.
